Des. 230,812

Patented Mar. 19, 1974

230,812

COMBINED STOVE TOP COOKING SURFACE AND FRAME THEREFOR

Robert A. Bruce, Painted Post, N.Y., assignor to
Corning Glass Works, Corning, N.Y.

Filed Aug. 2, 1971, Ser. No. 168,528

Term of patent 14 years

Int. Cl. D7—02

U.S. Cl. D7—121

Fig. 1

Fig. 2

Fig. 3

FIG. 1 is a perspective view of a combined stove top cooking surface and frame therefor embodying my new design.

FIG. 2 is a top plan view.

FIG. 3 is a front elevational view.

I claim:

The ornamental design for a combined stove top cooking surface and frame therefor, as shown.
